UNITED STATES PATENT OFFICE.

HARRY A. SPILLER, OF BOSTON, MASSACHUSETTS, ASSIGNOR, BY MESNE ASSIGNMENTS, TO BROWN-BINNAN COMPANY, OF BOSTON, MASSACHUSETTS, A CORPORATION OF MASSACHUSETTS.

DISK CLOSURE FOR JARS AND SIMILAR RECEPTACLES.

No. 895,906.

Specification of Letters Patent.

Patented Aug. 11, 1908.

Application filed November 18, 1907. Serial No. 402,614.

To all whom it may concern:

Be it known that I, HARRY A. SPILLER, of Boston, in the county of Suffolk and State of Massachusetts, have invented a new and Improved Disk Closure for Jars and Similar Receptacles; and I hereby declare that the following is a full, clear, and exact description of the same, reference being had to the accompanying drawings, forming part of this specification.

This invention has reference to improvements in disk closures for receptacles and particularly to such closures for milk jars.

One object of this invention is to so construct a disk closure formed of paper, card board or similar fibrous material that printing on said disk cannot be affected by the finishing process to spread the printing ink over the surface of the disk.

Another object of the invention is to so construct a disk closure of this nature that the action thereon of vacuum holding means may be facilitated.

Another object of the invention consists in so protecting the printing matter on a disk closure of this nature that the contents of the receptacle on which the disk is designed to be used cannot come in contact with such printed matter.

The invention consists in the disk closure hereinafter described and claimed.

In the drawings: Figure 1, represents the improved disk in plan view. Fig. 2, is a sectional view thereof taken on line 2—2 Fig. 1.

Similar numerals of reference designate corresponding parts in both figures.

Disk closures for food receptacles such as milk jars are generally formed from paper or card board which, because of its fibrous nature, is treated with wax or similar material adapted to close the pores of the paper and to supply a finished surface thereto. As these disk closures must be produced at very small cost the utmost economy in the manipulation of the material during the process of its manufacture must be effected and particularly after the disks have been printed and cut out from the main body of the material for, after such cutting out the disks must be carried forward individually to receive the wax coating and to be polished.

The mechanism for carrying forward disks after they are printed forms no part of the present invention but, if a vacuum carrier be

used, it is desirable to so prepare the disk as to facilitate its adhesion to such carrier and this is one of the objects of this invention.

It is obviously desirable that the disk closure be provided with some name, mark, or inscription indicating the nature of the contents of the receptacle, to which the closure is intended to be applied, or the manufacturer or shipper of said contents. This marking of the closure is generally accomplished by printing the mark or name on one surface of the closure but, when so printed in the ordinary manner, this method of manufacture is objectionable for several reasons among which is that in the waxing and polishing process the printers' ink, applied practically on the surface of the closure, is acted upon by the polishing devices and is spread over the surface of the cap thus producing a blurred appearance; again as the polishing of the disks removes the surplus wax and tends to flatten the disk around the very slight impression, if any, of the ordinary printing, the ink is practically uncovered and may come into contact with the contents of the receptacle and may have a deleterious effect thereon; this is particularly so when, through inadvertence, the printed side of the closure is turned towards the contents of the receptacle to which the closure is applied.

In carrying this invention into practice I print the desired mark, or inscription and ornaments directly into the body of the disk to a substantial depth whereby when the cut out disks are brought within the action of the air passing to a vacuum carrier such depressed portions being in the nature of vacuum chambers may facilitate the adhesion of the disk to said carrier during the application of wax and the polishing of the reverse surface of the disk or during other operations.

As shown in the drawings, in enlarged scale the disk closure has the obverse surface 5 in which is impressed to a substantial depth depressions 6—6 having any desired shape in plan view to form letters, characters or symbols and having at the bottoms of said depressions layers or bodies 7—7 of color applied thereto by the printing form by which such depressions are formed under more than the ordinary printing pressure. Transparent wax applied to the surface 5 in any ordinary manner partially fills the depressions 6—6 nearly to the plane of the sur-

face 5, the shrinking of the wax and the polishing process leave the surface of the wax slightly below the surface 5 as indicated by the line 8 Fig. 2 so that the finished product 5 has a slight depression in the nature of a vacuum chamber. The bodies of wax are anchored at their edges in the edge walls of the depressions 6—6 and prevent access of fluid to the coloring matter at the bottoms of said 10 depression and resultant deleterious effect of either on the other while the color is visible through the semi transparent wax or similar waterproofing material.

Having thus described my invention I 15 claim as new and desire to secure by Letters Patent.

1. A closure for milk jars and similar re-

ceptacles comprising a fibrous disk having a depression coated with waterproofing compound.

2. A closure for milk jars and similar receptacles comprising a paper disk having depressed therein, to a substantial depth, a depression or depressions, said depressions having coatings of transparent waterproofing 25 material.

3. A closure for milk jars and similar receptacles comprising a disk having a series of depressions of substantial depth, and bodies of wax in said depressions.

HARRY A. SPILLER.
